(57) **CLAIM**

The ornamental design for a wearable ECG monitor, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view showing a wearable ECG monitor, of our new design;

FIG. 2 is a rear view thereof;

FIG. 3 is a side perspective view thereof;

FIG. 4 is a side perspective view thereof, opposite FIG. 3;

FIG. 5 is a bottom perspective view thereof; and,

FIG. 6 is a top perspective view thereof.

The portions of the wearable ECG monitor that are shaded red are for illustrative purposes only and form no part of the claimed design.

1 Claim, 6 Drawing Sheets
